UNITED STATES PATENT OFFICE.

ROBERT SIEGFRIED, OF PITTSBURG, PENNSYLVANIA, ASSIGNOR TO
WESTINGHOUSE ELECTRIC & MANUFACTURING COMPANY, A COR-
PORATION OF PENNSYLVANIA.

HELICAL SPRING.

No. 817,135.

Specification of Letters Patent.

Patented April 3, 1906.

Original application filed May 22, 1905, Serial No. 261,673. Divided and this application filed January 3, 1906. Serial No. 294,410.

To all whom it may concern:

Be it known that I, ROBERT SIEGFRIED, a citizen of the United States, and a resident of Pittsburgh, in the county of Allegheny and State of Pennsylvania, have invented a new and useful Improvement in Helical Springs, of which the following is a specification, this application being a division of my application, Serial No. 261,673, filed May 22, 1905.

My invention relates to helical springs and it has for its object to provide a device of this character which shall serve to resiliently oppose pressure exerted against any and all portions of its periphery, as well as against its ends or against pressure exerted in either of said directions alone.

My invention is primarily designed for utilization as a cushion device between an internal boss or core and the inner cylindrical wall of a surrounding chamber; but it is my intention to have it utilized in any relation where its special structure and functional characteristics may render its use desirable.

In the accompanying drawings, Figure 1 is an end view of a spring constructed in accordance with my invention, and Fig. 2 is a longitudinal sectional view of the spring shown in Fig. 1 and two coöperating members.

As will be seen by reference to the drawings, each turn of the helical spring 1 is offset from the adjacent turns, so that the centers of curvature of the several turns are out of alinement with each other, and if a cylindrical core 2 of the maximum diameter to fit within the spring is introduced, no one of the turns will engage such core for any considerable portion of its length, and no two adjacent turns will engage the core at corresponding points or portions. While the relation of the several turns each to the other may be varied from that here shown, the general arrangement here indicated will give the best results, since the locus of the centers of curvature of the several turns or convolutions constitutes a helix, and therefore the points of contact of the interior of the spring with the core and of the exterior of the spring with a cylindrical chamber 3, in which it may be located, will be distributed more uniformly than would be the case if a different arrangement of turns were employed, and therefore the distribution of the cushion effect is the maximum for this character of device.

As here shown, the stud 2 is provided with a sleeve 4, and the chamber 3 is provided with a lining 5, to be engaged by the spring, and by referring to Fig. 1 it will be seen that the spring makes contact with each of these members along three lines, which are substantially one hundred and twenty degrees apart. While this exact relation of parts is not essential, it affords a satisfactory distribution of pressures and is probably more desirable than any other arrangement.

The spring here shown and described will generally be made of tempered resilient metal, such as steel, in order to provide the maximum efficiency; but my invention is not limited to any specific material or to any specific use.

I claim as my invention—

1. A helical spring comprising a plurality of convolutions of which no two adjacent convolutions are concentric.

2. A helical spring comprising a plurality of convolutions, the locus of the centers of curvature of which constitutes a helix.

3. A helical spring comprising a plurality of convolutions all adjacent convolutions of which are displaced laterally with respect to each other.

4. A helical spring having a plurality of mutually eccentric convolutions.

5. A spring-cylinder comprising a series of convolutions that are uniformly spaced apart and at least a portion of which are mutually eccentric.

6. A helical spring the adjacent turns of which are relatively displaced, in combination with an inclosing and an inclosed cylinder with which the spring makes contact along three lines substantially one hundred and twenty degrees apart.

7. A helical spring having its adjacent convolutions laterally displaced and having interior and exterior bearing-points along lines that are substantially one hundred and twenty degrees apart.

In testimony whereof I have hereunto subscribed my name this 29th day of December, 1905.

ROBERT SIEGFRIED.
